UNITED STATES PATENT OFFICE.

DOROTHY ABBOTT, OF COVINGTON, KENTUCKY.

DESIGN FOR A STATUETTE.

Application filed May 4, 1922. Serial No. 2,087. Term of patent 14 years.

To all whom it may concern:

Be it known that I, DOROTHY ABBOTT, a citizen of the United States, residing in the city of Covington, county of Kenton, and State of Kentucky, have invented a certain new, original, and ornamental Design for a Statuette, of which the following is a specification, reference being had to the accompanying drawing, forming a part thereof.

Fig. 1 is a front view, and Fig. 2 is a side view, of a statuette, showing my new design.

I claim:

The ornamental design for a statuette as shown.

DOROTHY ABBOTT.
